KEY ACTION FOR ORGANS INCLUDING MODULAR ROTARY WIPING CONTACT SWITCH

Paul A. Klann, P.O. Box 2398, Waynesboro, Va.

Filed July 22, 1963, Ser. No. 296,830

11 Claims. (Cl. 200—164)

This invention relates to improvements in key actions for organs and especially to a key action for organs including a silent rotary wiping contact switch of the modular type which switch is not limited in its use to the environment of organ key actions.

In electric organs as well as pipe organs, each of the keys on the various keyboards, the pedals, stops and other similar operator actuated devices, are utilized to control a plurality of intermediate electrical switches which in turn control the ultimate sound producing devices. These key or pedal or stop operated intermediate switches are often formed in a matrix arrangement so that the keys and stops may provide a number of different combinations in the sound produced. These intermediate switch assemblies are commonly known as key actions. Key actions may be directly coupled to manual keyboards or pedal boards or they can be remotely controlled by relays and other arrangements commonly known in the organ art. This invention relates to an improved key action and includes as a component of the key action a silent rotary wiping contact switch having a modular construction, the switch being capable of uses other than in key actions.

In key actions for use in organs it is quite obvious that silent operation is essential so that noise of operation of the key action does not interfere with the music produced. This invention utilizes a unique construction in a key action including a rotary contact switch biased in its bearings by contact wires to provide silent operation.

In organ consoles where key actions are commonly located, space economy is important. That is, there is only a certain amount of space within an organ console and if large numbers of different combinations are required for the key action, for example a great number of slides, it becomes essential that the key action construction be quite small. This invention provides a key action which utilizes a construction so that a great number of slides may be positioned close to one another and thereby provide a very compact key action.

Because of the construction of the rotary wiping contact switch of this invention, only a very small amount of power is necessary to operate the switch so that this key action is useful not only as a manual key action but also as a remote key action actuated by small power rotary solenoids or the like.

The rotary wiping contact switch of this key action has a unique construction, which not only has high contact pressure and wiping action to break any insulating film which might form on the switch contacts but also which can be modified for additional flexibility. The possible modifications include providing numerous independent isolated electric circuits from one switch or providing sequential actuation of a number of contacts by means of a twisted switch rotor.

A further feature of the key action of this invention which is especially attractive is that no adjustment of the key action is needed or required.

Furthermore, the key action and rotary switch of this invention are quite simple in construction and can be made of relatively low cost materials. The simplicity leads to ease of manufacturing and assembly and consequently the key action is comparatively inexpensive.

Other objects and advantages of the invention will be pointed out in the following description and claims and

2

illustrated in the accompanying drawings which disclose, by way of example, the principles of this invention and the best mode which has been contemplated of applying those principles.

5 In the drawings:

FIG. 1 is a top plan view of the key action of this invention with a number of the component parts not shown or broken away for the sake of clarity in illustration.

10 FIG. 2 is a side elevational view, partially in section, of the key action shown in FIG. 1 and similarly has a number of the components not shown or broken away for the sake of clarity in illustration.

15 FIG. 3 is a sectional view taken along line 3—3 of FIG. 1 with a further showing of a key for actuating the key action.

FIG. 4 is an enlarged perspective view of the slides and contact wires forming a portion of the contact switch within the key action.

20 FIGS. 5 and 5A are detailed views illustrating the position of the key action switch in normally unactivated and activated positions respectively.

FIGS. 6 and 6A show the position of the switch rotor similar to FIGS. 5 and 5A but with the switch contact wires moved away from possible circuit closing by a slide.

25 FIG. 7 is a perspective view of the switch contact rotor of the preferred embodiment.

FIG. 8 is an elevational view of a modified form of switch contact rotor for isolating electric circuits.

30 FIG. 9 is an elevational view of a further modification of switch contact rotor for sequential actuation of contacts.

FIG. 10 is a perspective view of an electric switch utilizing the modular rotary wiping action contact switch of the key action showing a rotary solenoid actuator and additional leaf spring switches.

35 Referring to the drawings, and especially to FIG. 1, a key action 10 includes in general, a support 12, and a multiple electric switching matrix 14 composed of a plurality of rotary wiping contact switches 16 and selectively actutable slides 18.

40 The support 12 includes a pair of side rails 20 and 21. Side rail 21 may have a plurality of spring attachment tabs 22 extending therefrom, one of which is shown in FIG. 3. The side rails 20 and 21 are rigidly spaced apart by a 45 slide guide 24, a magnet support 26 and other suitable spacers, not shown.

45 The rotary wiping contact switches 16 include a rocker arm 28 journaled in side rails 20 and 21 and extending through a central bore in a plastic contact rotor 30. The 50 rocker arm 28 is nonrotatably held in contact rotor 30 for driving the same. The rotor 30 is shown in detail in FIG. 7 and includes a plurality of grooves 32 formed in the plastic and separated by lands 33. A contact bar 34 is embedded in the plastic rotor by molding the plastic 55 around it and the contact bar extends parallel to the rotor axis so that it is accessible within the grooves 32.

55 A plurality of contact wires 38 are molded in a plastic support 40 or the like and support 40 is attached to side rails 20 and 21 as shown in FIG. 3. The contact wires 60 may have a flattened portion at 42 to control the bending thereof, see FIG. 4. As shown in FIGS. 1 and 3, the contact wires 38 are spaced apart a distance equal to the 65 grooves 32 in rotor 30 and are biased against the rotor within these grooves. Thus, the contact wires tend to ride in the grooves. In some angular positions of the rotor 30 the contact wires 38 will contact the contact bar 34 and establish an electrical circuit or circuits. This is 70 shown for example in FIG. 5A. In other angular positions of rotor 30 the contact wires 38 will merely ride in the grooves 32 and the contact bar 34 will be positioned away from the wires 38 so that a circuit will not be made.

This latter arrangement is shown in FIG. 5 and, in a key action, is the normal position until a key is operated. For holding the rotor 30 in this normal position, a biasing spring 36 is provided. The spring 36 is attached to tab 22 and to an extension 52 on the rocker arm 28. There will, of course, be a rotary wiping contact switch and biased rocker arm for each key of the key action, although for the sake of simplicity only one is being described in detail.

As shown in FIG. 3, a conventional key 44 includes an adjustment clip 46 secured thereto and having an adjustment screw 50 for determining when the clip will contact the rocker arm extension 52. A pad of felt 48 or the like to assure silent operation is attached to the end of clip 46.

The selectively actuatable slides 18 include a plurality of elongated thin wires 54 as shown in FIG. 1 and each of these wires has a plurality of spaced plastic hooks 56 molded thereon. The spacing of the plastic hooks 56 on wires 54 corresponds to the spacing of each row of wires 38. The wires 54 are guided in slots in the slide guide 24 and the hooks 56 are positioned around each of the wires 38, see FIGS. 1, 2 and 4. In order to enable a pair of hooks to go into the space between two wires the hooks are staggered in horizontal planes as shown in FIG. 2. Springs 58 attached to the support are provided for biasing the wires to the right as viewed in FIGS. 1 and 2. The springs cooperate with a plastic reverse hook 60 molded onto the end of each slide wire 54. The other end of each wire 54 is secured to a plastic eye 74 so that the slides may be axially moved against their spring bias by operation of magnets 62. Due to the close spacing of the slide wires 54 and the greater width of the magnet 62, the magnets have to be staggered in several rows as shown for example with two staggered rows in FIG. 1. There will usually, however, be several additional staggered rows to accommodate the large number of slides.

As shown in FIG. 2, each of the magnet assemblies 62 includes a coil 64 on a core 66 having a curved tip. A pivoted armature 68 is supported at pivot bearing 70. An actuator extension 72 is provided on the armature and this extension mounts the plastic eye 74 to which the slide wire 54 is connected. Suitable felt stops 67 and 69 may be provided on stop bracket 76 and coil 64, respectively, for deadening the sound and controlling the extent of movement of armature 68 and slide wires 54. The extent of movement of the slide wires is such that the hooks 56 will never completely clear their corresponding contact wires 38. The arrangement of the contact wires 38 and hooks 56 is shown in detail in FIG. 4. A modification of a hook that is totally enclosed to prevent the possibility of the slide wire becoming disengaged is shown as hook 56a in FIG. 4. In this modification the width of the enclosed slot is controlled for stable operation.

The operation of the key action and the rotary switch therein will now be described. Suitable electrical leads for establishing the desired electrical circuits are connected to the bottom end of the contact wires 38 and similarly, suitable leads for operating various slides 18 are connected to the selected magnet 62. These electrical connections are well known in the organ art. On the operation of one or more keys 44, movement of the key upward about its pivot (not shown) as illustrated by the arrow in FIG. 3, causes rotation of the rocker arm 28 which mounts the contact rotor 30 for the corresponding key or keys. Rotation of the contact rotor 30 causes the contact bar 34 to move from the position as shown in FIG. 6 to the position shown in FIG. 6A or from the position shown in FIG. 5 to the position shown in FIG. 5A. Whether or not circuits will be made through the corresponding contact wires 38 depends on whether or not the slides 18 are in open or closed position, see FIG. 1. If the corresponding magnet 62 for a selected slide wire 54 is actuated it will overcome the bias of spring 58 and allow the wire to move into the groove 32 and cor-

respondingly mate with contact bar 34 depending on whether or not the corresponding key has been actuated to rotate rotor 30. For magnets that have not been energized the springs 58 pull the contact wires 38 connected to the corresponding slide wire 54 out of possible contact with the rotor contact bar 34 as shown in FIGS. 6 and 6A. Although the arrangement has been shown with the slides biased to a position normally retracting the contact wires 38, the device could be arranged to normally allow the wires 38 to ride in grooves 32 and the magnets could be energized for the moving of the wires 38 away from possible contacts such as shown in FIGS. 6 and 6A. There will, however, be enough contact wires 38 resting against each rotor 30 to bias the rotor and its mounting rocker arm 28 within its mounting support so that there will be little noise in operation. That is, the operation will be silent due to the fact that the principal moving parts, the contact rotors, are biased in their support bearings.

10 The switch rotor 30, slides 18, and contact wires 38 with support 40 can be easily manufactured of wire with plastic moldings thereabout and are simply and easily assembled. Also, by the use of such composite plastic and metal moldings, the device is easy to mass produce and inexpensive in construction, and no adjustment is needed or required. By having the slides 18 formed of wire with small plastic hooks in staggered planes they can be quite close together allowing the use of a great number of slides in the space previously required for only a few.

20 The rotary wiping contact switch of this invention is capable of various modifications and arrangements to enable it to provide great flexibility not only in key actions for organs but also in other arts. That is, the switch per se is not limited to its use in organ key actions. FIG. 8 shows one of the possible variations and modifications which may be made in the switch. FIG. 8 shows the contact rotor 30 of the switch having the grooves 32 separated by lands 33 of the plastic with a contact bar 34 embedded therein. In this modification, however, one of the lands 33 is split or sawed through so that a portion of the contact 34 is removed and effectively creates a second contact bar 34' in the same rotor. It will be apparent with the contact wires 38 riding in the grooves 32 that the rotor of FIG. 8 provides in effect several different isolated switches and thus can provide isolated circuits. As shown in FIG. 8, the contact bar 34 may be divided in several spots to provide as many isolated circuits as desired.

30 A further modification of the contact rotor is shown in FIG. 9. In this modification, the rotor 30 again has the usual grooves 32 separated by lands 33 and carrying the contact bar 34. However, the plastic rotor with the contact bar embedded therein is twisted so that the contact bar assumes a helix along an imaginary cylinder coaxial with the rotor. The twisted contact bar 34t will therefore make contact with the contact wires 38 in grooves 32 at different times during the rotation. In other words, contact bar 38 would contact a wire in the right-hand side of the rotor as viewed in FIG. 9 first and follow with consecutive contacts with other wires 38 in sequence going toward the left. This could be used in a key action for a crescendo effect and could be used in other switches for various other sequential actuation. Of course, the cut contact bar 34' of FIG. 8 could also be used in connection with the twisted contact bar 34t of FIG. 9 for further flexibility.

40 FIG. 10 shows a rotary solenoid actuating a contact rotor 30 used in a general switching arrangement, not specialized or limited to key actions for organs. In the arrangement of FIG. 10 there is a multiple contact diverge type switch utilizing the modular rotary wiping action switch disclosed above and it is noted that the contact rotor 30 has a flat back 82 for abutting against a leaf spring of a plurality of leaf spring switches 84. The rotor 30 also carries the contact bar 34 for contacting

a plurality of switch wires 38 as disclosed in connection with the FIGS. 1-7 embodiment. The leaf springs of leaf spring switches 84 abutting against the flat back of rotor 30 tend to hold the rotor in a normal position while actuation of the rotor not only can selectively close the circuits between contact wires 38 but also actuate the leaf spring switches 84 as desired. Rotation of the contact rotor 30 is accomplished by a rotary solenoid 86 which can include a coil 88 having a pivoted armature 90 mounted on a shaft 92 connected to the contact rotor 30. A rod 94 and base 96 make up a U-shaped flux path for the magnet to attract the armature 90 to the attracted position shown. It is obvious that the rotary solenoid could also be connected to the rocker arms 28 of the key action shown in the FIG. 1 embodiment to provide a remote rather than a manual key action. It is also apparent that the various forms of contact rotors shown in FIGS. 7-9 could be used as the contact rotor 30 in the switch and of course the leaf spring switches 84 could be omitted. The modular switch can be used in multiples as in the key action embodiment where the switches are positioned side by side or they can be positioned end to end for other uses.

While there have been shown and described and pointed out above the fundamental novel features of the invention as applied to the preferred embodiment and several additional modifications, it will be understood that various omissions, substitutions and changes in the form and details of the arrangement illustrated and its operation may be made by those skilled in the art without departing from the spirit of the invention. It is the intention, therefore, to be limited only as indicated by the scope of the following claims.

I claim:

1. A key action for organs comprising: 35
  - (a) a support,
  - (b) a plurality of rotatable contact rotors of insulating material journaled in the support with their axes parallel to one another,
  - (c) each contact rotor carrying a plurality of separate 40 but generally axially extending conductor bars embedded therein and a plurality of transverse grooves exposing the conductor within the grooves,
  - (d) a plurality of parallel rows of contact wires supported from the support, one row adjacent each 45 contact rotor and each contact wire biased into a groove of the rotor, the contact wires and rotor with contact bar being relatively angularly positioned such that rotation of the rotor moves the contact into and out of wiping contact with the contact wires,
  - (e) means connected to the rotor to cause rotation 50 thereof,
  - (f) a plurality of slides extending transverse to the axes of the contact rotors, each slide carrying means for contacting a contact wire in each row of contact wires for moving the same away from contact with the rotor,
  - (g) means for axially moving the slide to thereby move contact wires associated therewith into and out of biasing contact with the rotor groove,
  - (h) spring means attached to the support and to one 55 end of each slide wire for biasing the slide wires out of contact with the rotor groove, and
  - (i) magnet means connected to the other end of each slide wire for moving the slide wire in the opposite direction to allow the slide wire to be biased into the grooves of the contact rotor.

2. A key action as defined in claim 1, wherein each of the plurality of slides comprises a slide wire having a plurality of insulated plastic hook portions molded thereto, the hook portions spaced apart a distance equal to the distance between the parallel rows of contact wires.

3. A key action as defined in claim 2, wherein each of the hook portions is closed and has an elongated aper-

ture of controlled width through which a contact wire extends.

4. A key action for organs as defined in claim 1, wherein the means to cause rotation of each contact rotor includes a key having a contact clip thereon, and a rocker arm extending through the contact rotor and adapted to be contacted by the contact clip on the key when the key is actuated.

5. A key action for organs comprising:

- (a) a support,
- (b) a plurality of rotatable contact rotors of insulating material journaled in the support with their axes parallel to one another, each contact rotor including a plurality of parallel transverse grooves in at least one portion of the surface thereof,
- (c) each contact rotor including means for providing separate isolated electrical circuits, said means including a plurality of separate but generally axially extending conductor bars embedded in the contact rotor and exposed within the grooves,
- (d) a plurality of parallel rows of contact wires supported from the support, one row adjacent each contact rotor and each contact wire biased into a groove of the rotor, the contact wires and rotor with contact bar being relatively angularly positioned such that rotation of the rotor moves the contact into and out of wiping contact with the contact wires,
- (e) means connected to the rotor to cause rotation thereof,
- (f) a plurality of slides extending transverse to the axes of the contact rotors, each slide carrying means for contacting a contact wire in each row of contact wires for moving the same away from contact with the rotor, and
- (g) means for axially moving the slide to thereby move contact wires associated therewith into and out of biasing contact with the rotor groove.

6. A key action for organs comprising:

- (a) a support,
- (b) a plurality of rotatable contact rotors of insulating material journaled in the support with their axes parallel to one another, each contact rotor including a plurality of parallel transverse grooves,
- (c) each contact rotor including means for allowing sequential action of a plurality of electrical circuits, said means including a generally helically extending conductor bar embedded in the contact rotor and exposed within the grooves,
- (d) a plurality of parallel rows of contact wires supported from the support, one row adjacent each contact rotor and each contact wire biased into a groove of the rotor, the contact wires and rotor with contact bar being relatively angularly positioned such that rotation of the rotor moves the contact into and out of wiping contact with the contact wires,
- (e) means connected to the rotor to cause rotation thereof,
- (f) a plurality of slides extending transverse to the axes of the contact rotors, each slide carrying means for contacting a contact wire in each row of contact wires for moving the same away from contact with the rotor, and
- (g) means for axially moving the slide to thereby move contact wires associated therewith into and out of biasing contact with the rotor groove.

7. A modular rotary wiping contact switch comprising:

- (a) a support,
- (b) a rotor body of insulating material journaled in the support,
- (c) a rotary solenoid including a pivotally mounted armature connected to the rotor body for rotating said rotor,
- (d) means defining substantially parallel grooves sep-

- arated by lands in the insulating body substantially transverse to the axis of the rotor,
- (e) an electrical conductor bar embedded in the insulating material of the rotor extending to the lands and exposed in the grooves of the rotor,
- (f) a row of contact wires, a wire for each groove of the rotor,
- (g) means supporting the row of contact wires so that they are inherently biased toward the center of the rotor to bias the rotor in its support and to allow wiping contact with the conductor upon rotation of the rotor, and
- (h) means for establishing at least some electrical circuits between the contact wires through circuits bridged by the conductor upon rotation of the rotor.
8. A modular rotary wiping contact switch comprising:
- (a) a support,
- (b) a rotor body of insulating material journaled in the support and including a flat back portion and spring means in contact with the flat back portion for holding the rotor in a normal position,
- (c) means for rotating said rotor,
- (d) means defining substantially parallel grooves separated by lands in the insulating body substantially transverse to the axis of the rotor,
- (e) an electrical conductor bar embedded in the insulating material of the rotor extending to the lands and exposed in the grooves of the rotor,
- (f) a row of contact wires, a wire for each groove of the rotor,

- (g) means supporting the row of contact wires so that they are inherently biased toward the center of the rotor to bias the rotor in its support and to allow wiping contact with the conductor upon rotation of the rotor, and
- 5 (h) means for establishing at least some electrical circuits between the contact wires through circuits bridged by the conductor upon rotation of the rotor.
9. A rotary wiping contact switch as defined in claim 8 wherein the spring means includes at least one leaf spring switch which is also actuated upon rotation of the rotor.
- 10 10. A switch as defined in claim 8, wherein the contact rotor conductor bar is a plurality of individual pieces to thereby form separate contact bars.
- 15 11. A switch as defined in claim 8, wherein a portion of the contact rotor and conductor carried thereby are twisted to cause sequential actuation of the switch upon rotation of the rotor.
